UNITED STATES PATENT OFFICE.

RUDOLPH JARY, OF CHICAGO, ILLINOIS.

AEROPLANE.

1,412,286.

Specification of Letters Patent. Patented Apr. 11, 1922.

Application filed December 27, 1920. Serial No. 433,350.

To all whom it may concern:

Be it known that I, RUDOLPH JARY, a citizen of the United States, and a resident of the city of Chicago, county of Cook, and State of Illinois, have invented certain new and useful Improvements in Aeroplanes, of which the following is a specification.

My invention relates to aeroplanes, and it has for its principal object the provision of new and improved form and arrangement of parts by which I shall be able to obtain increased carrying capacity, improved stability, and easier and more complete control of the machine in operation.

15 Other objects will appear hereinafter.

The invention consists in the combinations and arrangements of parts hereinafter described and claimed.

The invention will be best understood by 20 reference to the accompanying drawing forming a part of this specification, which drawing is a perspective view of my improved construction.

In the drawing, 5 indicates a closed car 25 of any approved type provided with carrying wheels 6 revolvably mounted thereunder. Transversely disposed above the car 5, I have provided two superposed planes 7 and 8 which are mounted in spaced relation with 30 respect to each other and in spaced relation with respect to the car, being held in operative position by any suitable means not illustrated. In rear of the planes 7 and 8, I have provided two additional superposed planes 35 9 and 10 which are also mounted in spaced relation to each other and in spaced relation with respect to the car, the upper and lower planes of the second pair being directly behind and in alignment with the upper and lower planes respectively of the first named 40 pair of planes. A fifth plane 11 is interposed between the upper planes 7 and 9 of the two pairs of planes, the plane 11 extending transversely at both sides beyond the 45 ends of the planes 7 and 9. The several supporting planes as above referred to are supported in operative position with respect to each other by the use of any approved means as is fully understood in the art.

50 For carrying the machine forward, I have provided propellers 12 and 13 mounted upon the horizontally disposed shafts 14 and 15 respectively which are driven by the use of any suitable power means. I have also provided a plurality of auxiliary propellers 16

mounted upon vertically disposed shafts 17, such propellers 16 being mounted within vertically disposed open cylinders 18 interposed within and extending between the upper and lower planes. By the use of the 60 horizontally disposed propellers 16, I am enabled to maintain the aeroplane in position in the air with a minimum of forward motion, the propellers 16 being driven through the medium of the shafts 17 from 65 any suitable source of power, either in union with the propellers 12 and 13 or independently thereof.

At opposite sides of the car 5, I have provided supporting wheels 19 upon the ends of 70 the plane 8, such supporting wheels 19 being disposed a short distance above the level of the supporting wheels 6. The aeroplane when in position upon the ground is designed to be supported by the wheels 6 of 75 the car, the wheels 19 being provided merely as auxiliary wheels for use for a landing operation.

Gas bags 20 of any suitable type are secured at opposite sides of the car below the 80 planes 8 and 10, the gas bags being designed to maintain the machine in position upon the surface of a body of water in case it is deemed desirable to land thereon.

For maintaining the aeroplane in position in the air and for assisting in guiding the motion of the machine during flight, I have provided an improved form of means 85 in rear of the supporting planes. This means comprises a horizontally disposed stabilizer plane 21 held in fixed position with respect to the supporting planes by means of suitable frame work extending rearwardly from the supporting planes. In the construction shown, the supporting frame work 90 or fuselage is in the form of a closed frame work comprising two arms 22 and 23. At the rear ends of the arms 22 and 23, I have provided vertically disposed planes or rudders 24 which are pivotally mounted upon 100 vertical axes with respect to said arms. Cables 25 are provided leading to the forward part of the machine for controlling the position of the rudders 24. Elevator planes 26 are provided on opposite 105 sides of the arms 22 and 23, a single intermediate elevator plane being provided between the arms. Each of the elevator planes 26 is pivotally mounted upon a horizontal axis with respect to the stabilizer plane 21, 110

the position of the elevator planes being controlled by the use of cables 27 of any approved type extending from the elevator planes to the forward portion of the machine. Below the rear end portions of the arms 22 and 23 I have provided auxiliary carrying wheels 28 of any approved type.

By the use of my improved construction, a very great carrying capacity is provided, 10 making the plane very desirable for use commercially or for use in warfare. By the provision of the horizontally disposed propellers, the operator is enabled to hold the machine in substantially stationary position in the air for photographing the position of the enemy in warfare or for enabling the operator to drop explosives at the desired point.

While I have illustrated and described the 20 preferred form of construction for carrying my invention into effect, this is capable of variation and modification without departing from the spirit of the invention. I, therefore, do not wish to be limited to the 25 precise details of construction set forth, but desire to avail myself of such variations and modifications as come within the scope of the appended claims.

Having described my invention, what I 30 claim as new and desire to secure by Letters Patent is:—

1. An aeroplane comprising a pair of superposed planes, a second pair of superposed planes secured in rear of said first 35 named planes and upon the same level therewith respectively, and a third plane bridging the gap between the upper two planes of said pairs of planes and extending transversely at its ends beyond the ends of said 40 first named planes.

2. An aeroplane comprising a pair of superposed planes, a second pair of superposed planes secured in rear of said first named planes, a third plane bridging the 45 gap between the upper two planes of said two pairs of planes and extending transversely from one end to the other of said planes; a propeller revolubly mounted on a horizontal axis on said aeroplane; means for 50 rotating said propeller; a vertically disposed open cylinder interposed in said planes and extending therebetween; a second propeller revolubly mounted on a verti-

cal axis in said cylinder; and means for rotating said second propeller. 55

3. An aeroplane comprising a pair of superposed planes, a second pair of superposed planes secured in rear of said first named planes, a third plane bridging the gap between the upper two planes of said 60 two pairs of planes and extending transversely from one end to the other of said planes, a propeller revolubly mounted on a horizontal axis thereon, means for rotating said propeller, a plurality of vertically disposed open cylinders interposed in said planes and extending therebetween at opposite sides of the machine, auxiliary propellers revolubly mounted on vertical axes in said cylinders, and means for rotating 65 said auxiliary propellers.

4. An aeroplane comprising a pair of superposed planes, a second pair of superposed planes secured in rear of said first named planes, a third plane bridging the 75 gap between the upper two planes of said two pairs of planes and extending transversely from one end to the other of said planes, a closed car for said aeroplane, carrying wheels revolubly mounted below 80 said car, wheels on said planes at opposite sides of the car above the level of the wheels on said car, and float members secured on said plane at opposite sides of the car for supporting the machine as a whole upon the 85 surface of a body of water.

5. An airplane comprising a pair of superposed planes; a second pair of superposed planes secured in rear of said first named planes; a third plane bridging the 90 gap between the upper two planes of said two pairs of planes and extending transversely from one end to the other of said planes; a pair of rearwardly extending spaced supports mounted on said planes; a 95 stabilizing plane connecting the ends of said supports; and vertical and horizontal rudders secured to said supports in rear of said stabilizing plane.

In testimony whereof I have signed my 100 name to this specification in the presence of two subscribing witnesses.

RUDOLPH JARY.
